(57) **CLAIM**

The ornamental design for a flying bird replica, as shown and described.

DESCRIPTION

FIG. 1 is an upper perspective view of a first embodiment of a flying bird replica showing my new design;

FIG. 2 is a top plan view thereof;

FIG. 3 is a bottom plan view thereof;

FIG. 4 is a front elevational view thereof;

FIG. 5 is a left side elevational view thereof, the right side being a mirror image;

FIG. 6 is a rear elevational view thereof; and,

FIG. 7 is a left side elevational view of a second embodiment thereof similar to the first embodiment seen in FIGS. 1–6, the difference being that the broken lines on the back have been removed.

The broken lines shown in FIGS. 1–6 illustrate environmental structure and form no part of the claimed design. The broken lines shown in FIG. 5 illustrate a transverse slot across the upper part of the body of the device.
